UNITED STATES PATENT OFFICE.

BURTON H. COOK, OF NEW YORK, N. Y.

BRUSH.

No. 832,656.

Specification of Letters Patent.

Patented Oct. 9, 1906.

Application filed July 13, 1904. Serial No. 216,446.

To all whom it may concern:

Be it known that I, BURTON H. COOK, a citizen of the United States, residing in the borough of Brooklyn, county of Kings, city 5 and State of New York, have invented certain new and useful Improvements in Brushes, of which the following is a specification.

This invention aims to provide certain improvements in brushes which are especially 10 adapted for use as bath-brushes or for any similar purpose, such as scrubbing floors or animals. In its preferred form a fountain-brush is provided—that is to say, a brush with means for supplying water either from 15 a reservoir at the back of the brush or by a continuous hose connection with a hydrant.

A particular point of improvement is in the means for carrying a supply of soap so as to furnish soapy water to the brush, and thus 20 make a lather by the simple brushing operation. The soap is held out of contact with the apertures in the back of the brush proper, so as to avoid the clogging which would occur if the soap were allowed to stand directly 25 upon the back after being softened by use.

Various improvements in detail are provided which facilitate the cleaning and use of the brush and which cheapen its construction.

30 The accompanying drawings illustrate embodiments of the invention.

Figure 1 is a longitudinal section of a complete brush. Fig. 2 is a side elevation from the opposite side of the brush, showing a 35 modified form of cover. Fig. 3 is a longitudinal vertical central section of a still further modified form of brush. Fig. 4 is an end view of Fig. 3.

The brush proper may be of any suitable 40 construction, which is shown as an ordinary bristle-brush with a back A of rubber or cel- luloid, so that it will not swell when wet, and having apertures B through which water can be admitted to the bristles C. The chamber 45 D, serving as a reservoir or as an intermediate passage when the brush is connected to a continuous supply, may consist of a sheet-metal rim provided with corrugations E E', which stiffen it, and the lower one of which 50 also serves as a stop to locate it on the brush- back. A removable cover is provided, which may be a simple flanged plate F, extending across the chamber D, as in Fig. 1, or a smaller and preferably round cover F', as 55 shown in Figs. 2 to 4, or both. In the latter case the cover F is provided with an opening

which the cover F' closes, this construction being shown at F² in Figs. 2-4. If only the cover F' is employed, the cover F² may be fixed to the walls of the chamber D instead 60 of being made removable therefrom. In this case the cover F² will serve as a top plate. If desired, the cover may be arranged to lock in place, so as to prevent its accidental removal by reason of the pressure of the water 65 inside. For this purpose a bayonet-joint may be provided, as shown in connection with the cover F', by forming an L-shaped depression G upon the flange L of the cover F², as indicated in dotted lines in Fig. 2, in 70 which depression a teat H, formed in the flange of the cover F', fits, or a spring-lock may be provided, as shown in connection with the cover F², such lock consisting of a slightly-elongated depression J at each end 75 of the reservoir, Figs. 3 and 4, into which snap teats K upon the cover F². The provision of the flange L, Figs. 2-4, forming a smaller opening at the center of the top of the chamber, has also an advantage in facilitating the 80 use of the chamber in the manner of a simple cup. Without connecting the brush to the continuous water-supply the cover F' may be removed and the water scooped up from a bath-tub or the like into the chamber D, 85 where it will be held in sufficient quantity to pass through the brush in the usual manner. In such case the brush may be held, with the hand of the user lying over the opening and practically closing the same, so as to hold the 90 water within the chamber.

A most valuable improvement is in the provision for carrying soap, whereby substantially a separate compartment is provided in the chamber, which holds the soap 95 close to the back of the brush, but out of contact therewith, and thus prevents the oozing of the soap into the apertures and the clogging of the same after the soap has been softened by use. With such a brush economy of soap is effected, it being possible to use small pieces which are otherwise thrown away. Medicated soap may be conveniently used, or any other medicinal, antiseptic, or similar substance may be used equally well. 105

As illustrated, the soap may be held up by a horizontal partition or tray M, which is perforated to let the soapy water pass through and which is held detachably in place by having its ends spring into grooves 110 N in the ends and sides of the chamber-wall. The cover F being removed, it is obvious

that the tray M can be easily removed. The chamber D, it is to be noted, may also be attached to the brush in a similar way, Figs. 3 and 4, to hold the two together against the ordinary water-pressure, while at the same time permitting the removal of the chamber by a strong pull, so as to facilitate cleaning the entire apparatus. A preferable form of tray M' is shown in Fig. 3 for holding the soap, being provided with a solid bottom and upwardly-extending scalloped sides O, drops of solder or similar projections P being arranged on the bottom of the tray to hold it slightly above the back of the brush. With this construction the soapy water fills the tray and runs over the scalloped edges and through the apertures into the bristles. The tray can be removed as a whole and cleaned with almost no difficulty. The inlet Q is so positioned as to admit water directly to the soap-compartment, a nipple R being provided for attachment of a small rubber hose S.

The brush may, if desired, be provided with a handle, which facilitates getting at ordinarily inaccessible portions of one's body. The handle T, where one is provided, is preferably made detachable—as, for example, by being screwed onto a stem U, attached to the chamber D.

It will be seen that the invention provides a brush capable of various uses, which by reason of the continuously-running water is extremely clean and sanitary, which is economical in construction and manufacture as well as in use, which does not readily clog, and the parts of which are easily accessible for cleaning. My improved brush is equally adapted for use with clear water—that is to say, without soap. Thus after using soap and making a good lather, the soap may be removed and the water run through clear, so as to spray the body with fresh water. The brush can be used either with or without a connection to a continuous supply of water.

Therefore, though I have described with great particularity of detail certain embodiments of the invention, yet it is not to be understood that the invention is limited to the embodiments disclosed. Various modifications thereof in detail and in the arrangement and combination of the parts may be made by those skilled in the art without departure from the invention.

What I claim is—

- 55 1. A brush having an apertured back, a chamber above said back, and means for carrying soap arranged close to said back, but separated therefrom, so that the soap is held out of contact with said apertures.
- 60 2. A brush having an apertured back, a chamber above said back, having an opening at its top adapted to admit a cake of soap, a

cover for said opening, and means extending substantially across said back for holding such soap out of contact with the back of the 65 brush.

3. A brush having an apertured back, a chamber upon said back for receiving water and admitting it to the apertures, and a removable device for holding soap in said chamber out of contact with said apertures.

4. A brush having an apertured back, a chamber upon said back for receiving water and admitting it to the apertures, a removable tray M' having scalloped edges and means 70 for supporting said tray above the back of the brush, an opening being provided in said chamber to admit water over the edge of said tray.

5. A brush having an apertured back, a 80 chamber upon said back for receiving water and admitting it to the apertures, said chamber having a free opening in its top adapted to permit water to pass into said chamber in use, said opening being smaller in size than 85 the top of said chamber, and said chamber being formed to permit said opening to be closed by hand to retain the water in said chamber.

6. A brush having an apertured back, a 90 chamber upon said back for receiving water and admitting it to the apertures, a removable device for holding soap in said chamber out of contact with said apertures, and a removable cover adapted to be locked on said 95 chamber.

7. A brush having an apertured back, a chamber formed of a band D extending around said back for receiving water and admitting it to the apertures, a removable tray 100 M' having upwardly-projecting sides O scalloped at the edge, means for supporting said tray a slight distance above the back of the brush, and a removable cover for said chamber.

8. A brush having an apertured back, a chamber formed of a band D extending around said back for receiving water and admitting it to the apertures, a removable tray M' having upwardly-projecting sides O scalloped at the edge, means for supporting said tray a slight distance above the back of the brush, a removable cover for said chamber adapted to be locked in place thereon, and a nipple R for connecting said chamber with a 110 water-supply.

In witness whereof I have hereunto signed my name in the presence of two subscribing witnesses.

BURTON H. COOK.
